UNITED STATES PATENT OFFICE.

JOHN AMES KIRK, OF BUCYRUS, OHIO.

DRAWING INSTRUMENT.

1,281,790.

Specification of Letters Patent. Patented Oct. 15, 1918.

Application filed April 1, 1916. Serial No. 88,366.

To all whom it may concern:

Be it known that I, JOHN A. KIRK, a citizen of the United States, residing at Bucyrus, in the county of Crawford and State 5 of Ohio, have invented certain new and useful Improvements in Drawing Instruments, of which the following is a specification.

My invention relates to drawing instruments and more particularly to a combination drawing instrument for drawing and spacing lines in parallel, drawing circles and for laying off working points.

The primary object of my invention resides in the provision of a spacing device 15 and novel means associated with the body of the ruler for coöperating with the spacing device, for facilitating the spacing of section lines at various angles.

Another object of my invention resides in 20 the provision of a novel compass arm adjustably mounted on the ruler for coöperating with the compass center point.

A still further object of my invention resides in the provision of mounting these 25 parts on a ruler so that they each coöperate to perform their various functions in an efficient manner.

A still further object of my invention resides in the provision of a device of the character described that is simple in construction, efficient in operation and one that can 30 be manufactured and placed on the market at a minimum cost.

Other objects as well as the nature, characteristic features and scope of my invention 35 will be more readily understood from the following description taken in connection with the accompanying drawings and pointed out in the claims forming a part of 40 this specification.

In the drawings:—

Figure 1 is a top plan view of my invention;

Fig. 2 is an enlarged transverse sectional view of the ruler showing to advantage the arrangement of the pawl and ratchet means for controlling the movement of the ruler when spacing lines;

Fig. 3 is an enlarged end elevational view

illustrating to advantage the arrangement 50 of the movable arm, a portion being broken away;

Fig. 4 is an enlarged end elevational view taken at the opposite end of the ruler;

Fig. 5 is an enlarged longitudinal sectional view illustrating to advantage the compass arm for holding the pencil;

Fig. 6 is an enlarged fragmentary sectional view showing the means for mounting the indicator and the movable sectional arm 60 on the ruler;

Fig. 7 is a fragmentary enlarged perspective view of one end of the ruler illustrating to advantage the manner in which the free end of the movable arm is associated 65 therewith when not in use.

Referring more particularly to the drawings in which similar reference numerals designate like or corresponding parts throughout the various views, I provide, a ruler 70 body 1 having a beveled edge indicated by the numeral 2, the upper surfaces of the body being provided adjacent the forward edge with a longitudinal groove 3 and also provided on its rear edge with a longitudinal recess 4. The body is further provided with a longitudinally extending slot 5 the ends of which are enlarged as indicated by the numeral 6 all for a purpose to be hereinafter described. 80

Disposed on the upper surfaces of the body conforming to the beveled edge 2 is a plate 7, said plate being provided with a longitudinal slot 8 which is arranged in registration with the slot 5 and also provided with a longitudinal slot 9 arranged in parallel relation with the slot 8 and in registration with the groove 3. 85

The ends of the plate are bent downwardly to conform to the ends of the body 90 as indicated by the numerals 10 and 11. Rotatably mounted in brackets 12 is a shaft 13. Carried adjacent the respective ends of the shaft 13 are supporting rollers 14. Spacing means coöperate with the shaft 13 and are 95 disposed adjacent one of the rollers 14 and consist of ratchet wheels 16 and 17, of different diameters secured to the shaft 13, and

a pawl 18 having an end 19 passing through the slot 9 and engaging one edge of the plate 7—Fig. 2.

Coöoperating with the spacing means on the ruler is my improved angle determining arm 21 having graduations thereon, one edge of which has a lateral extension which is bent upon itself as indicated by the numeral 22 and extending in an opposite direction and terminating in a point to serve as an indicator 23. The inner end of the arm 21 is provided with an opening as is the inner end of the indicator which openings are in alinement with each other for a purpose to be described. The end 10 is provided adjacent its upper edge with a slot 24 which permits the arm 21 to be extended into the pocket or recess 25 with the extension extending through the end 10. An extension 26 projects laterally from the lower edge of the end 10 and is bent upon itself within the recess 25 to provide a spring 27. When the arm is arranged within the recess, the indicator rests upon the plate 1, and in order to secure the parts in this position I provide a screw 28 which passes through the alined openings in the indicator on the arm and also through the alining openings in the plates 7 and the spring extension, said screw serving to frictionally maintain the parts in position while the spring serves as a yielding support for the arm. In procuring various angles I have scribed a segment of a circle 29 adjacent one end using the opening for receiving the screw as a center, also I have arranged graduations along the line. The pointed indicator 23 is arranged adjacent this circle and by adjusting the indicator with respect to the segment the desired angle is secured. When not in use the arm and indicator are swung inwardly, the arm being arranged within the recess 4, the outer end thereof which serves as a supporting leg 30 being arranged within a recess 31 in the opposite end 11 of the plate, this arrangement incidentally enhancing the appearance of the device.

To adapt the device as a compass a stud 32 is slidable in the slot 9 and has an arm 34 which is provided at its free end with a finger piece 37 and a marking point 36. A plate 35 is fitted in the lower face of the ruler and extends transversely thereof and each end is adapted to receive an element 39 provided with a point 38 which centers the ruler when striking a circle.

For drawing radii with either edge of the ruler as directing means, a plate 41 is transversely slidable on an end of the ruler, being held in the adjusted position by a screw 43 passing through a slot 42. An arm 45 is pivoted to the plate 41 at one end and its opposite end has a centering point 48 which may be brought in line with either edge of

the ruler and secured by a catch 49 at each end of the plate 41.

Although I have shown and described the preferred embodiment of my invention I desire it to be understood that I am not to be limited to the exact details shown, however, I desire that great stress be laid upon the movable arm for drawing section lines.

From the above description taken in connection with the accompanying drawings, it can easily be seen that I have provided a device that is simple in construction, containing but a few simple parts that can be cheaply manufactured and assembled and when assembled can be placed upon the market and sold at a low cost.

It will be understood that the above description and accompanying drawings comprehend only the general embodiment of my invention and that various minor changes in detail of construction, proportion and arrangement of the parts may be made within the scope of the appended claims and without sacrificing any of the advantages of my invention.

Having thus fully described my invention, what I claim as new and desire to secure by Letters Patent; is:—

1. A drawing instrument including a body having a slot therein and further provided with a recess, a metallic plate disposed on the body and provided with a slot arranged in registration with the slot of the body, means mounted in the slot for supporting the body, means for controlling the movement of the body, an arm pivotally connected to the body for swinging movement from the body and engaged in said recess when not in use, and an indicator extending from the movable arm and arranged upon the plate for determining the angular inclination of the arm from the body.

2. A drawing instrument including a body provided with a recess, a plate disposed on said body, an arm pivotally connected to the plate for swinging movement from the body and positioned in said recess when not in use, and an indicator extending from the movable arm and arranged upon the plate for determining the angular inclination of the arm with respect to the body.

3. A drawing instrument including a body having a recess formed therein, a plate upon the body extending beyond one end thereof and provided with scale markings and with a depending flange, a supporting tongue extending from the flange toward the body, the flange being provided with an opening, an arm pivotally connected with the tongue for swinging movement toward and away from the body and fitting into the recess when not in use, and an indicator extending from the pivoted end of the arm through the opening of the flange and bent

to extend across the plate in operative relation to the scale markings upon the plate.

4. A drawing instrument including a carrier, a depending flange at one end of said carrier provided with an opening, a support extending from the flange beneath the carrier, an arm pivotally connected with the support for swinging movement toward and away from the carrier, and a tongue extending from the arm through the opening

of the flange and extended upwardly and across the carrier to provide a pointer positioned in operative relation to the scale markings upon the carrier. 15

In testimony whereof I affix my signature in presence of two witnesses.

JOHN AMES KIRK.
